UNITED STATES PATENT OFFICE.

THOR ENGSTROM, OF PITTSBURGH, PENNSYLVANIA.

ERASER AND ERASER-HOLDER.

1,301,413.

Specification of Letters Patent. Patented Apr. 22, 1919.

Application filed September 6, 1918. Serial No. 252,836.

To all whom it may concern:

Be it known that I, THOR ENGSTROM, a citizen of the United States, residing at Pittsburgh, county of Allegheny, State of Pennsylvania, have invented certain new and useful Improvements in Erasers and Eraser-Holders, of which the following is a specification.

The present invention relates to erasers and eraser holders, and the principal object of the invention is to provide an ever ready device wherein the eraser will always be sharp enough to remove only the line or word intended to be removed.

In carrying out my invention I provide an eraser in the form of a thin strip of erasing material. I then use the structure of the holder to reinforce the eraser strip very near to its end and farther back also by applying pressure upon all its surfaces. Whenever it is necessary to feed the eraser a simple pressure upon the parts by the thumb and finger releases the holding pressure and allows the eraser strip to be fed along by hand. Because the erasing strip is thin, it need not be sharpened as would be the case were a thick eraser used. The holder is composed of a loop of spring metal and is shaped so as to readily fit the hand of the user. In case it is desired to erase a considerable area the eraser can be moved side-wise over the matter to be erased as it has a considerable width. The construction of the holder is such that it may be readily held whether operated to remove a single line or to erase a considerable area. In one case the sides of the strip may be readily gripped between the thumb and finger, while in the other case the thumb and finger engage angular extensions or wings provided for the purpose. The several features of the invention will be more fully understood upon referring to the following detailed description taken in connection with the accompanying drawing and the scope of the invention will be pointed out in the appended claims.

Referring to the drawings, Figure 1 is a perspective view of an eraser and its holder constructed in accordance with the present invention, showing the same held in the hand for the purpose of erasing a word or line of inappreciable width; Fig. 2 is a similar view illustrating the same parts when held in a position to erase an area of considerable width; Fig. 3 is a side elevation of the same eraser and holder; Fig. 4 is a sec-

tion-elevation of one-half of the holder, the section being a central one taken on a plane indicated by line 4-4 of Fig. 3; Fig. 5 is a side elevation of the eraser and holder; Fig. 6 is a transverse section taken on a plane indicated by line 6-6 of Fig. 3; Fig. 7 is a similar section taken on a plane indicated by line 7-7 of Fig. 3; and Fig. 8 is a section similar to Fig. 6 but showing parts of the holder without the eraser. Throughout these views like characters refer to like parts.

An inspection of the drawing will show that the eraser 10 is held by the holder 11. The latter consists of a strip of spring metal 70 formed into a loop having its lower ends 12 and 13 curved so as to provide two oppositely disposed parallel engaging faces. These faces are roughened by milling or otherwise, as indicated at 13'. The engaging faces are spring pressed toward each other by the resiliency of the metal composing the loop. When the eraser strip is removed, these oppositely disposed faces are pressed into engagement with each other as clearly illustrated in Fig. 8. When the eraser strip is in position then they engage its sides as clearly illustrated in Fig. 6. Besides having its sides engaged, the eraser strip 10 has its edges also engaged. This latter engagement is provided by the wings 14 and 15, wing 14 being formed as an extension of the end 12 and wing 15 being formed as the extension of end 13. The pressure which is applied to the edges of the strip 10 by the wings 14 and 15 is given, as a result of a bias in the tension of the loop 11 which tends to force the wings 14 and 15 toward each other. Thus it will be seen in Fig. 8 that the wing 14 abuts against the edge of the end 12. On the other hand, when the erasing strip 10 is in position, as illustrated in Fig. 6, the wing 14 presses against the edge of the strip 10 but does not engage the edge of end 12. By this structure it will be seen that pressure is exerted on all faces of the strip. In all instances the pressure is toward the center of the cross-section of the eraser strip. As clearly shown, the eraser strip 10 is then and thus provides a sharp 105 erasing edge which does not require sharpening. In order to support the strip near its erasing edge, the ends 12 and 13 are shaped to fit snugly against the sides of the eraser strip, especially at their lower extremities. 110 They are also rounded off as indicated at 16. This rounding of the extremities of the ends

12 and 13 closely conforms to the shape of the end of the eraser strip, after being worn a little in service. The rounding prevents the ends 12 and 13 from striking the surface 5 upon which the eraser is being used.

In order to free the eraser from the gripping action of the engaging faces so that it may be fed forward, I provide the loop 11 with slightly divergent faces 17 and 18 near 10 its edges at a point adjacent to the wings 14 and 15, as clearly illustrated in Figs. 3 and 7. These divergent faces are so positioned that they may be easily engaged by the thumb and finger of the user, and when so engaged, 15 a slight pressure will wedge the ends 12 and 13 apart so as to free the eraser strip 10 and allow it to be fed along as may be required. When erasing, the holder may be held as in Fig. 1 to erase a narrow strip or 20 area, and as viewed in Fig. 2 to erase a wide strip or area. In the first case, the movement of the strip is in the direction of its width, while in the latter instance the movement of the strip is at right angles to its width. In 25 the former case the thumb and finger engage the wings 14 and 15, while in the latter case they engage the flat sides of the ends 12 and 13.

From the above description it will be seen 30 that I have provided an eraser, including the eraser strip and holder, which will always be sharp and ready for use and one which will always erase the right amount. The device readily fits the hand and its ends 35 are also rounded so as to prevent interference with the surface on which the device is being used, and the cutting of the eraser strip when in use. By reason of the fact that the holder readily fits the hand of the 40 user, the work is done by a motion of the wrist and arm rather than by the motion of the fingers which easily tire. The wings also facilitate the gripping between thumb and finger and a slight pressure upon the 45 divergent faces enables the eraser strip to be readily fed. The latter strips may be provided in considerable lengths because of the space within the loop in which the strip lies. Obviously, it might be extended throughout 50 the length of the loop and still not interfere in any way with use of the device.

What I claim as new and desire to secure by Letters Patent of the United States is:

1. An eraser holder comprising a looped 55 strip of spring metal having its ends terminating in angularly disposed faces for engaging different surfaces of a strip of erasing material and biased to exert pressure on said eraser strip through all of the 60 engaged surfaces.

2. An eraser holder comprising a looped 65 strip of spring metal having its ends positioned so as to engage opposite surfaces of an eraser and wings on said ends positioned so as to engage other surfaces of said eraser,

said looped strip being biased to exert pressure through its ends and wings upon all the surfaces of the eraser engaged thereby.

3. An eraser holder comprising a looped strip of spring metal having its ends terminating in angularly disposed eraser-engaging faces, the faces on each end meeting in lines which extend in substantially the same direction as the plane of the loop formed by the strip, and said strip being 75 biased to exert pressure on the eraser through all of the eraser-engaged faces.

4. An eraser holder comprising a looped strip of spring metal having its ends positioned so as to engage opposite surfaces of 80 an eraser, wings on said ends for engaging other surfaces of the eraser, the eraser-engaging faces of the ends and wings meeting in lines which extend in the direction of the plane of the loop formed by the strip, and said looped strip biased to exert pressure on the eraser through 85 all the engaged surfaces.

5. An eraser holder comprising a looped strip of spring metal having its ends terminating in angularly disposed eraser-engaging faces, the faces on each end meeting in lines which extend in substantially the same direction as the plane of the loop formed by the strip. 90

6. An eraser holder comprising a looped strip of spring metal having its ends positioned so as to engage opposite surfaces of an eraser, and wings on said ends for engaging other surfaces of said eraser, the 100 eraser-engaging faces on the ends and wings meeting in lines which extend substantially in the direction of the plane of the loop formed by the strip.

7. An eraser holder comprising a looped strip of spring metal having at its ends opposed eraser-engaging faces extending at substantially right angles to the plane of the loop formed by the strip, and wings on said ends having opposed eraser-engaging faces extending in planes substantially parallel to the plane of said loop. 105

8. An eraser holder comprising a looped strip of spring metal having at its ends opposed eraser-engaging faces extending at 110 substantially right angles to the plane of the loop formed by the strip, said strip having other faces near said eraser-engaging faces on each side which diverge from each other outwardly whereby a slight pressure exerted by the thumb and finger of the user will wedge apart said eraser-engaging faces to allow the eraser to be fed along. 120

9. An eraser holder comprising a plurality of opposed eraser-engaging faces, 125 means for exerting pressure on the eraser through each of said faces, and means including outwardly diverging faces responsive to a pressure between the thumb and finger in the direction of the plane of said 130

eraser-engaging faces to wedge said eraser-engaging faces apart and separate them from the eraser to allow the latter to be fed along.

10. The combination with a thin strip of 5 erasing material, of a holding strip of spring metal in the form of a loop having its ends terminating each in a plurality of engaging faces extending in the direction of the erasing strip and operative to engage 10 different faces of said erasing strip, said metal strip being biased to exert pressure upon each of the engaged faces of said erasing strip.

11. The combination with a thin strip of erasing material, of means for reinforcing 15 the same near its end by applying pressure upon all surfaces of said strip, and means responsive to the application of pressure by the thumb and finger to relieve said reinforcing pressure to allow said strip to 20 be fed along.

In testimony whereof, I have hereunto subscribed my name this 3 day of September, A. D. 1918.

THOR ENGSTROM.
